PERCY TRIPP BAILEY, OF NEWPORT, RHODE ISLAND.

ANCHORING-BASE FOR POSTS.

952,404.

Specification of Letters Patent. Patented Mar. 15, 1910.

Application filed December 2, 1908. Serial No. 465,658.

To all whom it may concern:

Be it known that I, PERCY T. BAILEY, a citizen of the United States, and a resident of Newport, in the county of Newport and 5 State of Rhode Island, have invented a new and Improved Anchoring-Base for Posts, of which the following is a full, clear, and exact description.

This invention relates to anchoring bases 10 for posts.

The object of the invention is to provide an anchoring base of simple and durable construction, and one in which there are two sets of anchoring spikes which may be 15 driven into the ground after the base is set in position.

A further object is to provide a simple anchoring base which has means for adjustably supporting a fence post, whereby 20 the post may readily be alined.

The invention consists in the construction and combination of parts to be more fully described hereinafter and particularly set forth in the claims.

Reference is to be had to the accompanying drawings forming a part of this specification, in which similar characters of reference indicate corresponding parts in all the views, and in which—

Figure 1 is a front elevation, showing the anchoring base and the fence post in position; Fig. 2 is a horizontal section taken on the line 2—2 in Fig. 1; Fig. 3 is a section taken on the line 3—3 in Fig. 1; Fig. 4 is a 35 vertical section taken through the body of the anchoring base, showing one form of the driving head and the manner in which the anchoring spikes are inserted through said body; Fig. 5 is a similar section, showing a modified form of the driving head attached to the lower end of the body; Fig. 6 is an enlarged perspective view of the angular frame for supporting the upper set of anchoring spikes; Fig. 7 is a view similar 45 to Fig. 2, on an enlarged scale, showing a modified form of angular frame and anchoring spikes for use when the post is to be set near a wall; Fig. 8 is a front elevation showing a cap and fence post, together with a brace which is riveted in position; Fig. 9 is a plan view of a modified form of cylindrical bar having an elongated socket integrally formed therewith; Fig. 10 is a side elevation of said bar, partly in section; and 50 Fig. 11 is a vertical section through the cap and transversely of the sleeve.

The anchoring base is composed of a tubular body 1, which is open at both ends. In the construction shown in Figs. 1, 4 and 7, a driving head 2 is mounted in the lower end of the body 1, and may be fastened therein by means of rivets or in any other suitable manner. Said driving head comprises a substantially diamond-shaped point 4, which in the present instance may be 60 made hollow, in order to lighten the same. The upper portion or stem 5 of the head may be made substantially the width of the interior diameter of the body 1, and may be provided at its upper end with a cylindrical boss 6, adapted to act as a guide for the anchoring spikes. The head 2 is provided with laterally-extending shoulders 7, adapted to bear against the lower edge of 65 the tubular body 1.

In the modification shown in Fig. 5, the driving head 10 comprises a solid substantially diamond-shaped point 12, which is tapered on all four sides of its point, to form a pyramid. The stem 14 of the driving head extends into the lower end of the body 1, and is of sufficient width to span the interior diameter of the same. Said stem is also provided with a cylindrical boss 15 at its upper end, and with a stiffening web 16, 70 on opposite sides, intermediate its length. Said stiffening webs 16 also act as guides, in conjunction with the boss 15, for the anchoring spikes. Said driving head is provided with shoulders 18 resting against the 75 lower end of the body 1. These shoulders act as driving means whereby the body and the driving head may be forced into the ground.

Both forms of driving head are adapted 80 to be used with anchoring spikes 20 and 21, which may be formed of angle-iron and sharpened at their lower ends 22. The spikes 20 and 21 are slightly bent before being placed in the body 1. They are inserted 85 in the lower end of the body 1 before the driving head is inserted therein, and also before the body 1 is driven into the ground. By bending the ends of the spikes 20 and 21 slightly before placing them in the body 1, 90 it is easier to drive them, although it is not absolutely necessary that they be first bent. After the body 1 has been driven into the ground the desired distance, the spikes 20 and 21 are driven downwardly and deflected 95 by the driving head, as shown in Figs. 1 and 4.

An angular frame 30 is mounted about the tubular body 1 at some point below the surface of the ground. Said frame is composed of two similar angular members 31 and 32. The member 31 comprises a bar 34, which is curved at one end 35 and provided with a guide-slot 36 to form a supporting bridge. Said bar 34 is also provided with a strap or yoke 38, which may be 10 triangular in form in order to properly receive angle-iron anchoring spikes. A web 40 is connected with the bar 34, being placed diagonally of said bar and extending in a plane at right-angles thereto. Said web is 15 formed at its outer end into a tenon 41, adapted to enter a mortise 42 formed in the bar 46 of the angular member 32. The construction of the angular member 32 is the same as that set forth with respect to the 20 member 31, and comprises a web 44 placed diagonally of the bar 46 and extending at right-angles thereto. Said web 44 is provided at its outer end with a tenon 48 adapted to enter a mortise 49 formed in the 25 bar 34. The tenons 41 and 48 are to be riveted over, in order to fasten the frame together. A screw-threaded hole 43 may be provided in one of the webs for a set-screw, for a purpose to be hereinafter set forth.

30 By reference to Figs. 2 and 6, it will be seen that the angular frame formed by the members 31 and 32 forms a substantially rectangular guide for the tubular body 1, but the opposing sides of said frame are 35 inclined in opposite directions, as will be clearly seen in Fig. 1. The angular member 32 is provided with a guiding slot or bridge 50, and a guide-yoke or retaining strap 51 similar to those on the member 31. The 40 anchoring spikes 52 and 54 are formed of angle-iron, and may be curved, as shown in Fig. 2.

45 In Fig. 7, I have shown a modification of the angular frame and upper set of anchoring spikes for use when the post is to be placed near a wall which extends into the ground. Said modified angular frame 76 may be composed of a member 81 comprising a bar 82 having a bridge 83 and a retaining 50 strap 84 similar to the member 31. A web 85 similar to the web 40, projects from the member 82. An angular member 86 forms the opposing portion of this angular frame, and comprises a flat bar 87 having two retaining straps 88 thereon and a laterally-projecting web 89, provided with a threaded hole for the reception of a set-screw 90. The bars 82 and 87 are inclined in opposite directions, and may be riveted to the webs 55 89 and 85. A spike 92 is retained by the straps 88, and said spike is formed straight, in order that it may not come in contact with the wall 94. The spike 95 may be similar to the spike 52.

60 65 The angular frames may be made to fit

tightly or loosely about the body 1 and be placed about said body after it is in position in the ground. For use in sections of the country where frost does not heave posts, said frames may be made to fit tightly. 70 When used in locations where the frost is likely to heave the posts, the frames are made to fit loosely, and are held in position about the body 1 by the set-screw 90, while the upper set of anchoring spikes 52, 54, or 75 92, 95 are being driven into position. After said spikes are driven, the set-screw is removed, thereby allowing the body 1 to rise and fall through the angular frame under the action of the frost. The flexibility of 80 the lower spikes 20 and 21 is sufficient to enable them to yield to this action.

From the construction above set forth, it will be seen that there are two sets of anchoring spikes, deflected in different planes 85 and acting to firmly hold the body within the ground.

In order to suitably mount a fence post, or any other similar form of post, I provide a cap 60, which fits over the upper end of 90 the tubular body 1, and may be held in place thereon by means of a set-screw 62. The interior of said cap is beveled at 61, in order to provide a firm seat for the cap against the upper end of the body 1, and the 95 lower end of said cap may be formed with an internal flange 63 which fits the outer periphery of the body 1. Said cap is formed integrally with a sleeve 64 and provided with a set-screw 65. A cylindrical bar 66 100 may be held within the sleeve 64 and be provided on one end with a lug 67 adapted to co-act with a similar lug 68 formed on a socket 69 for holding the post 70. The socket 69 is provided with a set-screw 71 for 105 adjustably securing the post 70 therein. A bolt 72 is passed through the lugs 67 and 68 and held therein by means of a nut 73. The posts may sometimes be of such a shape that they may be fastened to the bar 66 directly 110 without the use of a socket. The post 70 may be provided with a collar 75, secured thereto by a set-screw 76^a, and having a brace 77 connected to the collar, as shown in Fig. 1. The lower end of the brace 77 may 115 be provided with holes 78 for the reception of a screw 79, which may be threaded into a boss 80, formed on the cylindrical bar 66. If desired, the brace 77 may be slotted, instead of being provided with the plurality of 120 holes 78, or the bar 66 may be so constructed that a set-screw may be mounted therein, to press against the side of the brace 77, as will be readily understood.

In Fig. 8 is shown a brace 100, which is 125 riveted at 101 to the collar 75, and at 102 to the lug 80 on the cylindrical bar 66. The alinement of the post 70 is obtained by sliding the collar 75 along the post, and then tightening the set-screw 76^a and the nut 73. 130

In Figs. 9 and 10 is shown a modified form of cylindrical bar 105, adapted to enter the sleeve 64, and provided on one end with an elongated socket 106 having internal webs 107, and on its other end with a lug 108, adapted to form a support for a brace 77 or 100. The socket 106 is provided with a set-screw 109 for holding a post 110, which may be tilted in said socket, as indicated by the 10 dotted lines in Fig. 9.

From the construction of the cap and post supports above set forth, it will be seen that the position of the post may be varied by rotating the cap 60, and the inclination of the 15 post may be varied by means of the other adjustments, and then the post may be secured in adjusted position.

Having thus described my invention, I claim as new and desire to secure by Letters Patent:—

1. An anchoring base for posts, comprising a hollow body, a driving head at the lower end of said body, anchoring devices held within said body and deflected by said 25 driving head, a cap secured to said body and provided with an integral sleeve, an angular frame mounted about said body and provided with oppositely-inclined guiding means, and anchorage arms held in said 30 guiding means.

2. The combination of an anchoring base body, a cap inclosing the upper end of said body and secured thereto, said cap having a sleeve integral therewith and extending 35 across the upper portion of the same, a horizontally-disposed bar slidably mounted in said sleeve, a post socket at one end of said bar, a post mounted in said socket, and a brace secured to the other end of said bar 40 and to said post at a point above the bar.

3. An anchoring base for posts, comprising a tubular body having an open lower end, a driving head within the lower portion of said body and rigid in respect thereto, said driving head having a lower terminal point extending beyond said body, a stem portion extending across the diameter of said body and having laterally-extending shoulders in engagement with the lower end of the 50 body to limit the upward movement of the head in respect to the body, and anchorage arms frictionally held in said body upon opposite sides of said driving head and having their lower ends extending out through the 55 open lower end of the body and deflected in opposite directions by said driving head.

4. An anchorage base for posts, comprising a tubular body, a frame surrounding said body and composed of two members secured together, each of said members including a side bar, each of said bars having one end thereof curved outwardly and provided with a guiding slot and having a strap or yoke adjacent the opposite end thereof, 60 and anchorage arms, each held within the

strap and guiding slot of its corresponding bar.

5. An anchoring base for posts, comprising a tubular body having an open lower end, a driving head within the lower portion 70 of said body and rigid in respect thereto, said driving head having a lower terminal point extending beyond said body and a stem portion extending across the diameter of the body, and anchorage arms frictionally held 75 in said body upon opposite sides of said driving head and having their lower ends extending outwardly through the open lower end of the body and deflected in opposite directions by said driving head. 80

6. The combination of an anchoring base body, a horizontally-disposed bar secured thereto at the upper end thereof, said bar having a post socket at one end thereof, a post pivotally mounted in said socket and 85 extending upwardly at substantially right angles and having its upper end movable laterally to vary the angle of the post in respect to the bar, and a brace secured to said bar and to said post at a point above the 90 bar to lock the post against lateral movement.

7. The combination of an anchoring base body, a horizontally-disposed bar secured thereto at the upper end thereof, said bar having a post socket at one end thereof and longitudinally movable in respect thereto, a post pivotally mounted in said socket and extending upwardly at substantially right 95 angles and having its upper end movable laterally to vary the angle of the post in respect to the bar, and a brace secured to said bar and to said post at a point above the bar to lock the post against lateral movement. 100

8. The combination of an anchoring base body, a cap inclosing the upper end of said body and secured thereto, said cap having a sleeve integral therewith and extending across the upper portion of the same, a horizontally-disposed bar slidably mounted in said sleeve, said bar having a post socket at one end thereof, a post mounted in said socket and extending upwardly at substantially right angles and movable laterally to vary the angle of the post, and a brace secured to said bar and to said post at a point above the bar to lock the post against lateral movement. 110

9. The combination of an anchoring base body, a horizontally-disposed bar secured thereto and having a post socket pivotally secured to one end thereof, a post mounted within said socket, and a brace adjustably secured to the opposite end of said bar and to said post at a point above said bar. 120

10. The combination of an anchoring base body, a horizontally-disposed bar pivotally secured thereto at the upper end thereof to swing in a horizontal plane, said bar having a post socket at one end thereof, a post piv- 125 130

otally mounted in said socket to swing in a vertical plane and normally extending upwardly at substantially right angles to the bar, and a brace secured to said bar and to 5 said post at a point above the bar to lock said post against movement in respect to the bar.

In witness whereof I have signed my name to this specification in the presence of two subscribing witnesses.

PERCY TRIPP BAILEY.
